UNITED STATES PATENT OFFICE.

WILLIAM O. ALBIG, OF ADRIAN, MICHIGAN.

COMBINED BLACKING CONTAINER AND DAUBER.

1,303,531.

Specification of Letters Patent. Patented May 13, 1919.

Application filed May 26, 1916. Serial No. 100,011.

To all whom it may concern:

Be it known that I, WILLIAM O. ALBIG, a citizen of the United States, residing at Adrian, county of Lenawee, State of Michigan, have invented a certain new and useful Improvement in Combined Blacking Containers and Daubers, and declare the following to be a full, clear, and exact description of the same, such as will enable others skilled in the art to which it pertains to make and use the same, reference being had to the accompanying drawings, which form a part of this specification.

This invention relates to an improvement in devices for applying blacking to shoes and its object is a combined polish or blacking container and dauber of an improved form as hereinafter described by means of which the blacking may be directly applied to the shoe from the container avoiding the soiling of the hands of the user. Another object is a device for applying blacking to boots or shoes that is cleanly in use and of a form preventing a waste of the blacking. 25 With the ordinary metal boxes now in use for containing blacking the polish is usually first transferred to a cloth and from the cloth to the shoe. In the device herein disclosed the container is in the form of a collapsible tube and the blacking is in paste form adapted to be forced through the end of the tube into a dauber secured to the discharge end thereof. The dauber is provided with a cap in order that the blacking 30 in the dauber may not be exposed to atmosphere when not in use, and thus dried out and further provides a closure or cover for the dauber enabling the device to be readily carried in a traveling bag without danger 35 of soiling the material with which it may come in contact. These and other objects and the several novel features of the invention are hereinafter more fully described and claimed and shown in the accompanying 40 drawing in which—

Figure 1 is a perspective view of my improved form of paste container and dauber and the cap therefor.

Fig. 2 is an elevation of the device showing the dauber and cover in section.

Fig. 3 is a similar view showing the dauber as arranged for use.

Similar characters refer to similar parts throughout the drawing and specification.

55 The blacking to be used for this device is of the consistency of a paste, and the body

of the container, as indicated at 1, is in the form of a tube similar to that now used in a container for tooth paste, soap paste and the like. The discharge end of the tube is 60 preferably formed by casting the lead of which the tube is made to form a flat face 2 having the discharge opening 3. The flat face 2 is formed with a circumferential flange 4 beveled on its upper edge at 11. A 65 dauber 5, preferably of lamb's wool is secured to the flat face 2 either by gluing the hide portion to it or in some other approved manner. The hide or leather portion of the wool dauber preferably extends over the 70 bevel 11 on the edge of the flat face 2, for the reason hereinafter described.

An annular cover member 6, preferably of sheet metal, is carried at the discharge end of the container and loosely mounted 75 relative to the dauber and plate. Each end of the annular cover member 6, is internally flanged as indicated at 7, leaving a central aperture through each end substantially equal in diameter to the diameter of the tube 80 and preferably slightly less in diameter than the diameter of the flange 4 on the face 2. This cover member is provided with screw threads 8, and is movable longitudinally of the dauber and tube. A cap 85 member 9 for the member 6 is provided and adapted to be threaded on the member as indicated in Fig. 2. By this arrangement the dauber is sufficiently protected from atmosphere to prevent the drying out of the paste 90 in the lamb's wool in the intervals between the ordinary use thereof and enables the device to be carried loosely in an ordinary traveling bag without danger of soiling articles coming in contact therewith.

When it is desired to use the dauber the cap 9 is removed from the cover member and said cover member moved downwardly relative to the tube which exposes the lamb's wool as indicated in Fig. 3. The leather portion of the lamb's wool being slightly greater in diameter than the supporting face 2, and therefore contacting the member 6, the edge of the leather is engaged by the upper flange 7 of the cover member and forced down onto the beveled edge 11, which produces a sufficient pressure on the leather portion and flares the fiber of the wool outwardly over the edge of the cover as indicated in Fig. 3.

By collapsing the wall of the tube by pressure of the hand of the user a portion of

- the paste, as indicated at 10, in Fig. 3 is forced outwardly into the lamb's wool whereupon the same may be directly applied to the shoe, using the tube as a handle for the dauber. By working the dauber over the surface of the shoe practically all of the paste that is forced into the dauber may be worked onto the surface of the shoe leaving the dauber comparatively free of paste. 10 The shoe may then be polished in the ordinary manner with a brush or polishing cloth.

After use the cover member may be drawn upwardly over the lamb's wool as indicated 15 in Fig. 2, the cap 9 placed thereon, and the device may then be handled without soiling the hands of the user. By the arrangement described a container for the paste becomes a handle for the dauber in applying the 20 paste to a shoe, and by combining the dauber and container the dauber can not be misplaced.

From the foregoing description it becomes evident that the device is of a simple 25 nature, very handy, and is very efficient and convenient in operation.

Having thus briefly described my invention, its utility and mode of operation, what I claim and desire to secure by Letters Patent 30 of the United States is—

1. A device of the character described comprising a collapsible tube for blacking provided with an externally flanged discharge end, a centrally apertured dauber 35 mounted at the discharge end, a ring shaped cover member for the dauber having internal flanges at each end engaging over the flanged portion of the tube preventing removal of the ring from the tube, said cover member being adapted to be moved longitudinally of the tube to cover or uncover the sides of the dauber, and a cap for the said dauber.

2. In a device of the character described, 45 a container for shoe blacking consisting of a collapsible tube having a substantially flat faced centrally apertured discharge end, a dauber member having a flexible base cemented to the said flat face and having an

aperture registering with the aperture 50 therein, a cylindrical open ended cover member adapted to be moved longitudinally of the tube to cover or expose the dauber, the cover member having an internal flange at the forward end adapted to engage the 55 flexible base on movement to expose the dauber, and a cap for the cover member.

3. A device of the character described comprising a collapsible container for blacking having a discharge conduit at one end 60 forming a flat face, said flat face being beveled on the outer edge thereof, a dauber member consisting of lamb's wool having a leather backing, said backing projecting over the bevel on the flat face, a ring shaped 65 cover member for the dauber engaging the projecting edge of the said backing and being movable to cover or expose the sides of the dauber, movement of the cover to expose the dauber tending to flare the wool fibers 70 over the end of the cover member, and a cap adapted to be secured to the cover member.

4. A combined blacking container and dauber comprising a collapsible tube providing a handle, a dauber member secured 75 to the discharge end thereof into which blacking may be delivered into the tube, said dauber having a flexible backing free to be flexed about the periphery thereof, and a 80 cover member for the dauber capable of longitudinal movement on the tube and adapted to engage the free edge of the said backing when moved to expose the dauber substantially as and for the purpose described.

5. A combined blacking container and 85 dauber comprising a collapsible tube provided with a flanged discharge end, a dauber having a flexible backing secured to the said end, said flanged portion being cut away beneath the edge of said backing, a cover member maintained in relation to the tube by the said flange and capable of longitudinal movement to engage the said backing and press the same over the cut away portion of said flange. 90

In testimony whereof, I sign this specification.

WILLIAM O. ALBIG.
